CLAIM

The ornamental design for an aircraft passenger service unit, as shown and described.

DESCRIPTION

FIG. 1 is an upwards view of an aircraft passenger service unit showing our new design in an aircraft cabin;

FIG. 2 is a front view of a first side of the aircraft passenger service unit of FIG. 1;

FIG. 3 is a front view of a second side of the aircraft passenger service unit of FIG. 1, opposite the first side;

FIG. 4 is a perspective view of the first side of the aircraft passenger service unit of FIG. 1;

FIG. 5 is a perspective view of the second side of the aircraft passenger service unit of FIG. 1;

FIG. 6 is a close-up view a portion of the aircraft passenger service unit, as indicated in FIG. 1; and,

FIG. 7 is an end view of the aircraft passenger service unit of FIG. 1.

In FIGS. 1-7, the dash-dash broken lines illustrate the environment of the design and portions of the aircraft passenger service unit that form no part of the claimed design. The dot-dash broken lines illustrate the periphery of the enlarged views of the aircraft passenger service unit and form no part of the claimed design.
